(57) **CLAIM**

The ornamental design for a speaker for a phone, as shown and described.

DESCRIPTION

FIG. 1 is a top, front, and left side perspective view of a speaker for a phone of the present invention, shown without the charging dock for ease of illustration;

FIG. 2 is a top view thereof, shown without the charging dock for ease of illustration;

FIG. 3 is a front view thereof, shown without the charging dock for ease of illustration;

FIG. 4 is a right side view thereof, shown without the charging dock for ease of illustration;

FIG. 5 is a bottom view thereof, shown without the charging dock for ease of illustration;

FIG. 6 is a top, front, and left side perspective view thereof;

FIG. 7 is a top view thereof;

FIG. 8 is a front view thereof;

FIG. 9 is a right side view thereof;

FIG. 10 is a bottom view thereof;

FIG. 11 is a back view thereof; and,

FIG. 12 is a left side view thereof.

The broken lines in the figures illustrate the portions of the speaker for a phone and form no part of the claimed design.
